UNITED STATES PATENT OFFICE

HARRY V. BALL, OF CONCORD, MASSACHUSETTS, ASSIGNOR TO R. HOE & CO., INC., OF NEW YORK, N. Y., A CORPORATION OF NEW YORK

ASSOCIATING MECHANISM

Application filed April 20, 1927. Serial No. 185,147.

This invention relates to certain improvements in large multi-press arrangements in which each press includes a plurality of printing units.

It is the especial object of the present invention to provide a multi-press arrangement in which each press includes a plurality of printing units in which the presses are arranged side by side, with a space or aisle between for ready access to the printing units, so that a press arrangement of large capacity is provided in a compact form so as to minimize as far as possible the press room space required, the folders and web guides for the presses being so arranged that the units of each press may be associated in groups delivering to the folders of that press, or the products of the units of one press may be led across the aisle or space and associated with the products of some or all of the units of the other press, a wide range of products being obtainable by this arrangement.

A further object of the invention is to produce such a press arrangement in which the use of angle bars is eliminated or reduced, and in which the inside folding cylinders of the presses may be so arranged as to shorten the web run where the web or webs are led over one press to the other.

With these and other objects not specifically referred to in view, the invention consists in certain novel parts, arrangements and combinations which will be described in connection with the accompanying drawings and the novel features pointed out in the claims hereunto appended.

Two arrangements for effecting the objects of the invention are shown in the drawings. In one of these arrangements there are provided two presses, each press consisting of a plurality of units arranged side by side with a space or aisle between, each of these presses including a plurality of units and folders. The web guides are arranged to guide the webs of each press to a folder or folders of that press, or to guide a web or webs of one press, after they have passed the formers, across the aisle and associate them with the products coming from another press. In another arrangement there

are provided two presses superposed in two decks, each including a plurality of printing units and a plurality of folders, and two other presses superposed, each including a plurality of printing units and a plurality of folders, these presses being separated by a space or aisle, and web guides arranged to direct the webs to the folders of the presses on one side of the aisle or across the space or aisle and associate them with a web or webs of the other presses.

In these drawings,

Figures 1 and 1a show diagrammatically a plan view of one press arrangement embodying the invention, Figure 1a being a continuation of Figure 1;

Figures 2 and 2a show a side elevation of one of the presses shown in Figures 1 and 1a, Figure 2a being a continuation of Figure 2;

Figure 3 is a diagrammatic end view of the presses showing one arrangement of the folding and delivery mechanism and one lead of the webs;

Figure 4 is a view similar to Figure 3 showing a modification of the arrangement of the folding cylinders and one lead of the webs across from one press to another;

Figure 5 is a view similar to Figure 4 showing another lead of the webs;

Figures 6 and 6a show a diagrammatic side elevation of a second arrangement which may be employed, showing two presses superposed with the roll supplies above and below the printing mechanisms, and

Figure 7 is a diagrammatic end view, partly in section, taken at either end of the folders and showing two superposed presses on each side of the aisle or space, and a web run for crossing over from one pair of presses to the other across the aisle or space.

Referring first to Figures 1 to 5, one press arrangement selected to illustrate the invention comprises two presses P—P' arranged side by side, with a space or aisle 15 between them. In the machine illustrated, each of these presses includes six printing units, those of press P being marked 1 to 6 inclusive, and those of press P' being marked 7 to 12 inclusive. Each of the presses is provided with end folders and folders inter-

mediate certain of the printing units. As shown, the press P is provided with end formers A—A' and intermediate formers B—B', and the press P' is provided with end formers C—C' and intermediate formers D—D', and it will be observed that the folders and printing units of the two presses are arranged opposite one another.

It will be understood that this number of units and the arrangement of the folders have been selected as illustrative only of the invention, and that other units and folders can be added to the presses as desired, two such additional folders E—F being shown 15 in dotted lines in Figures 1a and 2a.

Each of the printing units, in the particular construction illustrated, is the same, and each unit, as shown, includes a printing and perfecting couple, the form cylinders of each 20 being marked 16, 17 and the impression cylinders 18, 19, the form cylinders being inked by inking mechanism indicated at 20. In the particular arrangement shown, where each press includes six printing units, each 25 press will be fed from six webs, those of press P' being shown and marked 21, 22, 23, 24, 25 and 26, which are fed into the presses over guide rolls 27, 28 and 29 from suitable sources of web supply, not illustrated. Each of the 30 formers, in the particular machine shown, is, as before indicated, a double former, the webs being slit by slitters 30 before passing over the formers.

Each former has cooperating therewith a 35 folding and delivery mechanism, and formers A—A' of press P and formers C—C' of press P' and their cooperating folding mechanisms are shown, it being understood that the same arrangement may apply to the formers 40 B—B', D—D'.

Referring first to former A, the web passes to a pair of forwarding rolls 31, 32, and from these to a pair of cooperating cutting and collecting cylinders 33, 34, the cylinder 34 45 being provided with sheet taking devices, as pins 35, and a folding blade 35', it being understood, of course, that these parts are supported in suitable framing of any desired character, not illustrated. From the cutting cylinders 33, 34, the products of former A 50 may pass to a fly 36 and be taken away from the press by a tape delivery 37. A guide roll 38 is also provided located between the forwarding rolls 31, 32 and the cutting and collecting cylinders, for purposes hereinafter 55 referred to.

The products are led from former A' by a 60 pair of forwarding rolls 39, 40 to a pair of cooperating cutting or collecting cylinders 41, 42, the cylinder 42 being provided with pins 43 and a folding blade 43', and the products from the cylinder 42 may be delivered to a fly 44 from which the products may be 65 taken from the press by a tape delivery 45. A guide roll 46, similar to the roll 38, is pro-

vided for the folding mechanism of former A' and, in addition, there is provided a pair of guide rolls 47, 48 located between the former A and the former A', which will hereinafter be referred to.

Referring now to formers C—C', the products from former C are taken off by a pair of forwarding rolls 50, 51 to a pair of cutting and collecting cylinders 52, 53, the cylinder 52 being provided with sheet taking pins 54 and a folding blade 54', and the products are forwarded to a fly 55, from which they are taken from the press by a tape delivery 56. The products from former C' are forwarded by a pair of forwarding rolls 57, 58 to cutting and collecting cylinders 59, 60, the cylinder 59 being provided with sheet taking devices, as pins 60', and a folding blade 60'', and from this cylinder the products are forwarded to a fly 61 and taken from the press by a tape delivery 62. A guide roll 63 is provided for the folding mechanism of former C and a guide roll 64 for the folding mechanism of former C', and located between the formers C—C' is a pair of guide rolls 65, 66, similar to the guide rolls 47, 48, before referred to.

With the mechanism so far described, it will be seen that the webs from formers A—A' may be led to either pair of cutting and collecting cylinders, as may be the webs from formers C—C'. In accordance with the invention, guides will also be provided whereby a web or webs of either press may be directed from below the formers of one press across the aisle to a former or formers of the other press for associating with the webs coming from the latter. Thus a wide range of products may be obtained without taking up undue space in the press room. Such an arrangement of guides is shown in 100 Figures 4 and 5, where to the right of former A' is shown a pair of guide rolls 67, 68, and to the left of former C is shown a pair of guide rolls 69, 70. It will also be observed that, as shown in Figures 4 and 5, the folding mechanisms of formers A' and C, that is, the inside mechanisms are offset with respect to their formers toward each other, so that the run across is shortened. This arrangement is a preferred one, but is not essential 105 and the arrangement can be as shown in Figure 3, if desired.

Referring now to Figures 3, 4 and 5, it will be observed that various runs of the web from formers A—A' and C—C' may be provided. Thus in Figure 3 the webs from former A' may be led over the guide rolls 47, 48 and 38 to the cutting and collecting cylinders 33, 34 and associated with the webs from former A, or the webs from each former may be directed to the respective cutting mechanisms of these two formers.

Similarly, the webs from former C' may be led over guide rolls 65, 66 and 63 and associated with the webs from former C at the 123

cutting cylinders 53, 54, or the webs may be led direct from these formers to their respective cutting cylinders.

If now a different product is desired, the webs from the formers A—A' may be associated and be led across the aisle 15 and associated with the webs from former C, this being effected after the webs from A—A' have gone past the formers, the webs being led from below the formers. Such an arrangement is shown in Figure 4, where the webs from former A pass over the guide rolls 47, 48 and 46' and meet the webs from former A' which pass over guide rolls 67, 48, the webs then going across the aisle and meeting the webs from former C at guide roll 70, the webs from former C going to roll 70 over guide roll 69, these webs thus being associated and being directed to the cutting cylinders 53, 54. In this particular arrangement the webs from former C' may go direct to cutting and collecting cylinders 59, 60.

In Figure 5 is shown a different run of the webs for producing other products in which all the webs from all the formers A—A' and C—C' may be associated, the webs from C—C' being led across the aisle, to one pair of cutting and collecting cylinders. In the arrangement shown in this figure, the webs from former C' are led over the guide rolls 65, 66, 63' and are associated with the webs from former C, which are led over the guide rolls 69, 70, these associated webs, after they leave the formers, crossing the aisle from below the formers and meeting the webs from formers A—A' at guide roll 68 and being directed to the cutting cylinders 41, 42. It will be observed that the guide rolls 47, 48, 65, 66, 67, 68 and 69, 70 are offset from each other, so as to compensate for the variations in the distances between the formers and the folding cylinders, where the web from one former is led across its folding mechanism to the folding mechanism of an adjacent former and thus insure the sheets being in the right position when they reach the folding cylinder.

It will be seen therefore, that various combinations of products can be obtained by the arrangement shown. It is important to note that by cross-associating the webs from below the formers and collecting, two products, each having a central double page, may be produced, which is desirable in some circumstances, as for instance where the printed matter of these pages is advertising.

The invention also provides means for obtaining great flexibility in arranging the various units in sets and combining their products without taking up undue space in the press room, and some of the combinations possible with the present arrangement will now be described.

Referring to Figures 1, 1a, 2, 2a, the units may be arranged so that they can deliver

their products together in sets of varying numbers without the webs passing over an idle folder. Thus, for instance, the webs from units 1, 2 and 3 may go to formers A—A'; the webs from units 4, 5 and 6 may go to formers B—B'; the webs from units 7, 8 and 9 may go to formers C—C', and the webs from units 10, 11 and 12 may go to formers D—D', this arrangement producing a combination of four sets of three units with no idle folder.

Or the webs from units 1, 2, after passing over the formers A—A' may be associated with webs from units 7 and 8 below the formers C—C'; or the webs from units 7 and 8, after passing over the formers C—C' may be associated with webs from units 1, 2 below the formers A—A'; webs from units 3, 4, 5 and 6 may be led to formers B—B'; and webs from units 9, 10, 11 and 12 may be led to formers D—D', this arrangement producing three sets of four units each without an idle folder.

Or the webs from units 1, 2, 3, 4 and 5 may be led to the formers B—B', and the webs 7, 8, 9, 10 and 11 to the formers D—D', this arrangement producing two sets of five couples each without passing over an idle folder; or the webs from the units of press P may be led to the formers B—B' and the webs from the units of press P' to the formers D—D', this arrangement producing two sets of six units without passing over a former; and, if desired, all the webs from the units of both presses may be associated below either of the formers B—B' or D—D' by cross-associating across the aisle, as above described.

By varying the location of the folders or adding more couples and their folders, various other arrangements can be provided.

The web guides for press P' have been shown in Figures 2 and 2a, and it will be understood that similar guides are provided for press P, and the runs of the webs have been shown in full and in dotted lines in Figures 2 and 2a, the guides for directing the webs being indicated generally by the numerals 75, 76.

The units may be driven in any suitable manner and this drive may be such that the presses may be driven either separately or synchronously, and such a drive is diagrammatically shown in dotted lines in Figures 1 and 1a, in which there are provided a shaft 80 for press P and a shaft 81 for press P', these shafts being connected by chain drive 82 with an intermediate driving shaft 83. The units and folders are driven from the shafts 80, 81 by the usual miter gears 84, these gears meshing with gears 85 on short vertical shafts 86, by which the mechanisms are driven.

Referring now to Figures 6, 6a and 7, a compact press arrangement is shown of large

capacity in which a very large number of different products may be obtained. For simplicity in showing, only the presses on one side of the aisle are illustrated. It will be understood that the mechanisms shown are duplicated on the other side of the aisle, as are the folders which are shown in Figure 7. In the construction illustrated, there is shown, arranged on one side of a space or aisle, marked 100 in Figure 7, two superposed presses, indicated generally by the letters X and Y. These presses are arranged superposed, the press Y being supported on floor 101, supported from standards 102 rising from any suitable base 103. The press Y will include a plurality of units arranged in line, these units being marked 104, 105, 106, 107, 108, 109, 110 and 111, supported in suitable framing 112. These units are identical and each comprises form cylinders 113, 114 and cooperating impression cylinders 115, 116. These units deliver to folders, indicated generally by the letters G and H. These units may be grouped in various ways, but in the particular construction illustrated there is a group of two, as units 104, 105—folder G, three units 106, 107, 108—folder H, and three units 109, 110, 111. These units are fed from webs 104', 105', 106', 107', 108', 109', 110' and 111', which are, as shown, located below the floor 101 feeding upwardly to the printing mechanisms.

Supported by the framing 112 is a floor or base 117, which supports the printing units of press X. In the particular construction illustrated, the printing units of press X are arranged above the printing units of press Y and are similarly grouped. Thus press X includes units 118, 119 with a folder I, units 120, 121 and 122 with a folder J, and units 123, 124 and 125, these units being supported in framing 126. Each of these units comprises form cylinders 127, 128 and cooperating impression cylinders 129, 130.

The units of press X are fed from webs 118', 119', 120', 121', 122', 123', 124' and 125', the web rolls from which the webs are fed being located above press X on a suitable support or base 131, the webs being fed downwardly to press X from the rolls.

As before stated, the press arrangement described is duplicated together with the folding mechanism on each side of the aisle or space 100, and the folders for the presses on each side will, preferably, be identical, and the folders I, G of the presses X, Y, and the folders I', G' of the corresponding presses across the aisle are shown in Figure 7 together with certain web leads which are shown as illustrative of the arrangement, it being understood that these web leads are equally applicable to any folders of the presses. Referring now to Figure 7, the folder I has a pair of formers 132, 133, the folder G has a pair of formers 134, 135, the

folder I' has a pair of formers 136, 137, and the folder G' has a pair of formers 138, 139. In the particular folder arrangement shown, only the folders G, G' are provided with folding cylinders, which are indicated by the numerals 140, 141, 142 and 143, these delivering to fly deliveries 144, 145, 143 and 147, from which the products are delivered in any suitable way, as by tapes 148 and 149.

The web leads across from folder G to folder G' or between the formers of folders G and G' are or may be as already described in connection with the folders of presses P and P', and need not be further referred to, the guide rolls there shown being omitted in Figure 7 for the sake of clearness. In addition to these leads, the webs going to folder I or to folder I' may be also led across to the folders of folder G' or vice versa, so that products of a wide range may be obtained.

In the particular construction shown in Figure 6 and 6a, the webs of presses X and Y are associated at the folders G and H, the webs from the upper folders I and J passing downwardly outside the other webs, as indicated at 150, 151 in Figure 7, and being associated with the webs from press Y at the formers of folders G and H. With the arrangement shown, all the webs have straight runs without the use of turning bars.

It will be seen from the above description that a press of great flexibility has been provided in which the units may be assembled in sets of different numbers without unduly lengthening the press, so that such a press can be installed in press rooms which do not require extraordinary or unusual space. Furthermore, by cross-associating the products of one press, after they have passed the formers and have been collected, a wide range of products can be obtained.

While the invention has been shown in its preferred form, it will be understood that certain changes and variations in the location of the folders relatively to the printing mechanisms and in the number of printing mechanisms and folders may be made without departing from the invention as defined in the appended claims.

What I claim is:

1. In a rotary multi-unit printing machine, the combination of two presses arranged side by side with a relatively wide aisle space between, each press including five or more printing units arranged in line the cylinders of which are positioned widthwise of the presses, formers for each press intermediate the units, web guides arranged to lead a web or webs across the space from below a former of one press and associate the led web or webs with web or webs coming from a former of the other press, and a delivery for each press arranged to deliver in opposite directions to each other.

2. In a rotary multi-unit printing machine,

the combination of two presses arranged side by side with a relatively wide aisle space between, each press including five or more units arranged in line the cylinders of which are positioned widthwise of the presses, end formers 5 for each press, other folders for each press intermediate the press units, web guides arranged to lead the webs from below the formers of one press across the space and associate the led webs with the webs coming from the other press, and a delivery for each press arranged to deliver in opposite directions to each other.

3. In a rotary multi-unit printing machine, 15 the combination of two presses arranged side by side with a relatively wide aisle space between, each press including five or more printing units arranged in line the cylinders of which are positioned widthwise of the presses, formers at the end of each press, intermediate 20 formers, folding cylinders below the formers, and web guides arranged to lead a web to a folding cylinder of its press, or to lead a web or webs across the space from below a former 25 of one press and associate the web or webs with a web or webs coming from a former of the other press, guides for directing the associated webs to a folding cylinder of the latter press, and a delivery for each press arranged 30 to deliver in opposite directions to each other.

4. In a rotary multi-unit printing machine, 35 the combination of two presses arranged side by side with a relatively wide aisle space between, each press including five or more printing units arranged in line the cylinders of which are positioned widthwise of the presses, end formers for each press, intermediate formers, folding cylinders arranged substantially horizontally and below the formers, the 40 inside cylinders being offset from their respective formers toward each other, and web guides arranged to lead a web or webs across from below a former of one press and associate the web or webs with a web or webs 45 coming from a former of the other press.

5. In a rotary multi-unit printing machine, 50 the combination of two presses arranged side by side with a relatively wide aisle space between, each press including five or more printing units arranged in line the cylinders of which are positioned widthwise of the presses, double wide formers for each press located intermediate the printing units, and web guides for leading all the webs of one press 55 from below the formers across the space and associating them at a former of the other press with the webs of the latter press.

6. In a rotary multi-unit printing machine, 60 the combination of two presses arranged side by side with a relatively wide aisle space between, each press including five or more printing units arranged in line with a space between the cylinders of each unit being arranged widthwise of the presses, double wide 65 end formers for each press, intermediate

double wide formers for each press, guides for leading the webs of one press to its end formers, and guides for leading all the webs from the formers of one press across the space to a former or formers of the other press.

7. In a rotary multi-unit printing machine, 70 the combination of two presses arranged side by side with a relatively wide aisle space between, each press including five or more printing units arranged in line the cylinders of which are arranged widthwise of the presses, two similar presses arranged above the first two presses, intermediate formers for each press, and web guides arranged to lead the webs over the formers of each press or to lead a web or webs after longitudinally folding from the upper presses across the space and then downwardly and associate such web or webs with a web or webs coming from one of the presses across the space.

8. In a rotary multi-unit printing machine, 75 the combination of two presses arranged side by side with a relatively wide aisle space between, each press comprising two printing units, a folder, three printing units, a folder and three printing units arranged in the order named, two similar presses and folders arranged above the first two presses, formers for each press, and web guides arranged to lead the webs over the formers of each press or to lead a web or webs after longitudinally folding from the upper presses across the space and then downwardly and associate such web or webs with a web or webs coming from one of the presses across the space.

9. In a rotary multi-unit printing machine, 80 the combination of two presses arranged side by side with a relatively wide aisle space between each press including five or more printing units arranged in line the cylinders of which are positioned widthwise of the presses, intermediate formers for each press, folding cylinders arranged substantially horizontally below the formers, the inside cylinders being offset from their respective formers toward 85 each other, and web guides arranged to lead a web across the space and associate it with a web coming from a former of the other press.

In testimony whereof, I have hereunto set my hand.

HARRY V. BALL.
